(57) **CLAIM**

The ornamental design for a tire, as shown and described.

DESCRIPTION

FIG. 1 is a perspective view of the tire of our design, according to a first embodiment;

FIG. 2 is a front elevation view of the tire of FIG. 1;

FIG. 3 is a side elevation view of the tire of FIG. 1;

FIG. 4 is a side elevation view of the tire of our design, taken from the opposite side of that shown in FIG. 3;

FIG. 5 is a perspective view of the tire of FIG. 1, taken from the opposite side of that shown in FIG. 1; and,

FIG. 6 is a detailed view of the tire as shown in FIG. 1.

The broken line disclosure in the drawings depicts environmental subject matter forming no part of the claimed design. The three-dimensional tread pattern repeats over the circumferential surface of the tread.
